UNITED STATES PATENT OFFICE

2,074,859

INTERNAL COMBUSTION ENGINE

George R. Rich, Battle Creek, Mich.

Application July 3, 1935, Serial No. 29,599

3 Claims. (Cl. 123—177)

This invention relates to internal combustion engines and more particularly to means for cooling the valves thereof.

One of the objects of the invention is to provide novel cooling means for the exhaust valves. It is well known that the hot gases in passing around unseated exhaust valves heat up the valves to such a high degree of temperature that frequently pre-ignition occurs.

10 A great many attempts have been made to remedy this defect, with little or no success. In accordance with the present invention, I provide a clearance space between the tops of the exhaust valves and the lower face of the usual water jacket, which clearance space, when a valve is lifted, is very slight, thereby permitting scarcely any of the hot gas to find its way over the tops of the exhaust valves while discharging from the cylinder.

20 The invention further consists in a valve having an upstanding flange or other projection, extending up from the top of the valve head and arranged to enter a water cooled pocket in the cylinder head, thereby practically isolating the top of the valve head from the hot gases and at the same time permitting heat to be absorbed from the valve. The bottom wall of the water jacketed cylinder head, being relatively cool, it absorbs heat from both sides of the flange on the 30 valve and, as a result, the valve is kept relatively cool.

The invention further consists of the several novel features of construction, arrangement and combination of parts, hereinafter fully set forth 35 and claimed.

The invention is clearly illustrated in the drawing accompanying this specification, in which:—

Fig. 1 is a vertical longitudinal section, through a fragment of a cylinder block and head of an 40 internal combustion engine, illustrating a simple embodiment of the invention applied thereto;

Fig. 2 is a cross section, taken on the line 2—2 of Fig. 1 showing the exhaust valve in closed position;

45 Fig. 3 is a horizontal section, taken on the line 3—3 of Fig. 2; and

Fig. 4 is a side elevation of the exhaust valve employed in the engine.

50 Referring to said drawing, which is merely illustrative of one embodiment of the invention applied to one cylinder of an internal combustion engine, the reference character 5 designates a fragment of a cylinder block, which contains a fragment of a cylinder block, which contains 55 the cylinder 17, and 6 designates the cylinder

head which is bolted thereto in the customary manner, as is well understood.

In the top wall 14 of the cylinder block is an inlet port 7 and an exhaust port 8, respectively, controlled by an inlet valve 9 and an exhaust valve 10, the stems 18, 19 of which are guided in valve guides 11, 12, as is customary.

The cylinder head is formed with a water jacket 13, the bottom wall of which has a raised part 15, which is spaced above the top wall 14 of the cylinder head to provide a passageway 16 between the cylinder 17 and the inlet and exhaust ports 7, 8, through which the combustible mixture is conducted from the inlet port to the cylinder and the burnt gases are conducted from the cylinder to the exhaust port.

20 The valve head 20, of the inlet valve 9, has a tapered face that seats upon a tapered seat around the inlet port 7, and the bottom wall 15 of the cylinder head is dished upwardly, as at 21, to provide a recess into which a head of the inlet valve is moved when fully opened, thereby leaving a free space below the bottom wall of the cylinder head for the passage of the combustible mixture to the cylinder.

25 The valve head 22 of the exhaust valve 10 has a tapered face that seats on a tapered seat around the exhaust port 8, and extending up from the margin of the valve head 22 is an upstanding annular flange 23 that serves to conduct heat away 30 from the valve.

Above the exhaust valve, the bottom wall 15 of the cylinder head is formed with an annular pocket 24, which is co-axially disposed with respect to the axis of the exhaust valve and is adapted to receive the annular flange 23 thereof when unseated. The pocket 24 may be formed by casting the bottom wall 15 around the pocket and, as shown, the pocket is contained between outer and inner annular upstanding walls 25, 26 40 connected at their upper ends by a horizontal annular wall 27. A circular wall 28 at the lower end of the inner annular wall 26 completes the wall construction around the pocket. Slight clearance spaces are left between the top of the 45 valve head (when lifted) and lower face of the wall 28 and between the flange 23 and adjacent faces of the upstanding walls 25, 26.

As is well understood, water is circulated 50 through the water jacket of the engine and the lower wall of the water jacket is kept relatively cool. Ignition of the combustible charge for any cylinder takes place while both valves are closed, and because the space over the top of the exhaust valve is closed by the flange 23 entering the pocket 55

24, the hot burning gases do not readily reach the top of the valve head.

When the exhaust valve is lifted, the annular flange 23 thereof enters the pocket 24 where it is exposed on both sides to the relatively cool walls 25, 26 of the water jacket, and heat radiating from the flange is absorbed by the relatively cool walls and the water contained in the water jacket. Heat radiating from the top of the valve head is absorbed by the wall 28 and the water in the water jacket.

From the above it is apparent that when the exhaust valve is lifted practically none of the hot burning gases come in contact with the top 15 of the valve head and that much of the heat developed in the valve is absorbed through the flange 23 by the surrounding walls of the water jacket.

The invention is applicable to internal combustion engines of all kinds employing poppet valves, such as automobile motors, truck motors, airplane motors, and the like.

More or less variation of the exact details of construction is possible without departing from 25 the spirit of this invention. I desire, therefore, not to limit myself to the exact form of the construction shown and described, but intend, in the following claims, to point out all of the invention disclosed herein.

30 I claim as new, and desire to secure by Letters Patent:

1. Cooling means for valves of internal com-

bustion engines, comprising in combination, a cylinder block having therein a cylinder and a valve opening, a water jacketed cylinder head having a bottom wall providing a passage between the valve opening and cylinder, said bottom wall having a pocket on its lower side, and a valve for controlling said valve opening and guided in the cylinder block, the valve having an upstanding part projecting above the top of its head and arranged to enter said pocket when the valve is 10 unseated.

2. Cooling means for the exhaust valves of internal combustion engines, comprising in combination, a cylinder block having therein a cylinder and a valve opening, a water jacketed head having a bottom wall spaced, in part, from the top of the cylinder block to provide a passageway between the valve opening and cylinder, said bottom wall having an annular pocket on its lower side, and an exhaust valve for controlling said 15 valve opening and guided in the cylinder block, the valve having an upstanding annular flange projecting up from the top of its head and arranged to enter said pocket when the valve is 20 unseated.

3. Cooling means for the exhaust valves of internal combustion engines, comprising a water jacket having a pocket on one side and a valve having a part projecting above its head and arranged to enter said pocket when the valve is 25 unseated.

GEORGE R. RICH.
